UNITED STATES PATENT OFFICE.

JOHN H. LEE, OF CHICAGO, ILLINOIS.

LINE-HOLDER.

SPECIFICATION forming part of Letters Patent No. 744,772, dated November 24, 1903.

Application filed February 28, 1903. Serial No. 145,216. (No model.)

To all whom it may concern:

Be it known that I, JOHN H. LEE, a citizen of the United States, residing at Chicago, in the county of Cook and State of Illinois, have 5 invented a new and useful Improvement in Line-Holders, of which the following is a specification.

My invention relates particularly to dashboard line-holders; and my primary object is 10 to provide a device of this character of exceedingly simple construction, great durability, and improved operation.

The invention is illustrated in the accompanying drawings, in which—

15 Figure 1 represents a broken perspective view of a dashboard equipped with my improved device; Fig. 2, a rear elevational view of the holder; Fig. 3, a section of the holder, taken as indicated at line 3 of Fig. 2; Fig. 4, 20 a plan view of a modification viewing a dashboard to which it is applied in section, and Fig. 5 a rear view of the modified form of holder.

Referring to Figs. 1, 2, and 3, A represents 25 a dashboard; B, a whip-socket; C, a whip; D, my improved line-holder, and E the lines secured by the holder. The device D comprises a dashboard clamp or clip a, a bolt a' therefor, and a spring or tongue a², between which 30 and the member a the lines are gripped. The clip a is preferably formed of sheet metal bent upon itself at a line b to afford jaws b'. The jaws b' are curved at their extremities to present concavities to each other parallel with

35 the line b and conforming to the dashboard-iron. Adjacent to and parallel with the line b the metal of the two halves of the clip is struck out to afford circular channels b² b³ for receiving the shank-wires of the tongue a². 40 The metal of each jaw is struck out also over an area b⁴, blending with the elevation at the channel b³, and from this raised portion b⁴ extend transverse ribs b⁵, whose extremities blend with the convex surface of the extremity 45 of the jaw. This materially strengthens the jaws, as is evident. The jaws are provided centrally with registering perforations countersunk by striking the adjacent metal inwardly. The tongue a² preferably is formed 50 from a single length of wire bent upon itself to afford a loop-form tip c and parallel adjacent members c'. The members are curved

forwardly to form the base c² of the tongue, then coiled to form opposite spirals c³ c⁴, and then extended upwardly from the rear portions of the coils to provide shank-sections c⁵ c⁶, received by the longitudinal or vertical channels b³ b² of the clamp. 55

The clamp is perfectly symmetrical with respect to the plane of the dashboard, so that 60 the tongue a² may be applied to form either a right or left holder. A screw-bolt preferably is employed in connection with the clamp, and this is reversible, the nut being used at the front side and the head being countersunk to afford a smooth surface for the lines. 65 In assembling the jaws are left unclosed to an extent which will permit ready application to the dashboard, and the shank-wires are forced into their channels under sufficient 70 pressure to prevent detachment under actual conditions of usage. The upper extremity of the tongue is suitably curved or hooked to permit ready insertion of the lines and finds a bearing upon the clamp between the raised 75 surfaces at the channels b² b³. The tongue inclines forwardly somewhat from its base upwardly, so that the space between it and the clamp narrows toward the upper end. The effect of this is to cause the tongue to 80 act to crowd the lines downwardly somewhat, thereby effectually preventing their accidental dislodgment.

In applying the device to a dashboard it is only necessary to slip the jaws over the rim 85 of the dashboard and tighten the screw, the springiness of the metal of the clamp yielding readily to the action of the screw. The device is convertible from right to left hand, or vice versa, or it may be supplied both right 90 and left handed by assembling properly, as is evident. The device can be fashioned by suitable stamping and bending operations and after assemblage of the parts is japanned or nickel-plated, affording an exceedingly 95 neat, light, strong, and durable construction. The channel for the lines is in a plane parallel with the dashboard, so that when the lines are inserted, as indicated, they are bent at right angles about the outer vertical edge of 100 the clamp. This aids also in preventing dislodgment of the lines. Of course, if desired, the device may be applied to the top of the dashboard.

In the modified form shown, D' represents a device comprising a clamp d', screw-bolt d', and tongue d². The clamp comprises spring-jaws d³ d⁴ and an extension d⁵ at the extremity of one of the jaws and lying adjacent to the inner surface of the dashboard. The tongue d² is like the tongue a², and the portion d⁵ has vertical channels d⁶ d⁷ for receiving its shank-wires. The metal is suitably shaped and bent upon itself some distance from one vertical edge to form the jaws and bent upon itself near its other vertical edge to form the channels for the shank-wires. The jaws are suitably strengthened by transverse ribs, as shown.

An advantage incident to the modified form is that the main portion of the device lies within the limits of the dashboard, so that there is but little projection beyond the edge 20 of the dashboard. It is obvious that the parts may be assembled to produce either a right or left hand holder. Here, however, the clamp requires to be inverted in the conversion, and for this reason the channels d⁶ 25 d⁷ are open at top and bottom. One wall of the channel d⁶ is shown struck in against the corresponding shank-wire, as indicated at d⁸, to give added security to the connection. In the other form the channels b² b³ are closed 30 at their upper ends, the adjacent upper margins of the jaws lying close together, producing a very neat appearance.

It will be obvious that changes in details 35 of construction within the spirit of my invention may be made. Hence no undue limitation should be understood from the foregoing detailed description.

What I claim as new, and desire to secure by Letters Patent, is—

40 1. A dashboard line-holder, comprising a suitable clamp, and a yielding tongue connected therewith and opposed to and bearing thereupon and forming therewith a channel, the channel between said tongue and clamp being parallel with the dashboard, for 45 the purpose set forth.

2. A dashboard line-holder, comprising an adjustable clamp having integral spring-jaws, and a tongue carried by said clamp and bearing 50 yieldingly thereon.

3. A dashboard line-holder, comprising a clamp provided with jaws for clamping upon the edge of the dashboard and having channels parallel with the edges of the extremities 55 of the jaws, and a tongue having upwardly extending shank-wires received by said channels.

4. A device of the character described, comprising a sheet-metal member bent to form 60 clamping-jaws and channels for shank-wires, and a tongue provided with shank-wires received by said channels.

5. A device of the character described, comprising a sheet-metal member bent to afford clamping-jaws, a screw for tightening said 65 jaws, and a tongue carried by said member.

6. A device of the character described, comprising a sheet-metal member bent to afford clamping-jaws, and a tongue carried by said member and forming therewith a line-receiving 70 channel parallel with the dashboard.

7. A device of the character described, comprising a sheet-metal member bent at its central portion to afford clamping-jaws and provided adjacent to its folded edge with channels, a suitable screw, and a tongue provided with shank-wires received by said channels. 75

8. A device of the character described, comprising a sheet-metal member folded upon itself at a central line and suitably shaped to 80 afford clamping-jaws, and provided adjacent to its folded edge with two channels, a suitable screw, and a tongue provided with upturned shank-wires received by said channels.

9. A device of the character described, comprising a sheet-metal member bent and shaped to afford clamping-jaws and provided with transverse stiffening-ribs at said jaws, and a tongue carried by and yieldingly opposed to 85 said member. 90

10. A device of the character described, comprising a sheet-metal member folded upon itself at a central line and suitably shaped to afford clamping-jaws and provided adjacent to its folded edge with channels parallel with 95 said edge and terminating beneath the upper edge, a suitable screw, and a tongue yieldingly opposed to said member and having shank-wires received by said channels.

11. A device of the character described, comprising a suitable clamp provided with channels, and a tongue carried by and yieldingly opposed to said clamp, and comprising a hook, coils and shank-wires formed integral with each other. 100 105

12. A device of the character described, comprising a clamp having laterally-extending jaws and vertical channels, and a tongue comprising a wire folded upon itself at its central portion and shaped to afford a hook, the members thereby formed being bent forward at the base, then coiled, then extended upwardly to afford shank-wires flanking the hook, said shank-wires fitting in said channels. 110 115

13. A dashboard line-holder of the character described, comprising a reversible clamp having jaws for clamping the edge of the dashboard, and a tongue reversibly connected with said clamp, for the purpose set forth.

JOHN H. LEE.
